UNITED STATES PATENT OFFICE.

JANE MELEY, OF SAN FRANCISCO, CALIFORNIA, ADMINISTRATRIX OF
HENRY M. TAAFFE, DECEASED.

AUTOMATIC GUARD OR TRACK-CLEARER.

SPECIFICATION forming part of Letters Patent No. 326,668, dated September 22, 1885.

Application filed May 4, 1885. (No model.)

To all whom it may concern:

Be it known that HENRY M. TAAFFE, late a citizen of the United States, and residing at San Francisco, in the county of San Francisco and State of California, now deceased, did invent a new and useful Improvement in Track-Clearers, of which the following is a specification.

The invention relates to improvements in track-clearers for railroad-cars, and it is especially applicable to the cars or dummies of endless-cable railroads; and the objects of the improvement are, first, to provide a cow-catcher or pilot with an outwardly or forwardly projecting transverse bar or bars formed of an elastic or semi-elastic material, which shall first receive the shock from any obstruction encountered upon the track; second, to provide an endless-cable railroad-car with a means whereby the impact from the collision of the dummy or pilot with an obstruction will be automatically and instantly transmitted to the grip mechanism, causing the same to relax its grip upon the cable or to drop the same; third, to provide an endless-cable railroad-car with a cable-gripping device so constructed and arranged that the collision of the said car with any obstruction upon the track will cause the pawl and ratchet of the brake mechanism to be instantly disengaged, permitting the gripping-jaws to separate and drop the cable. These objects are accomplished by the means illustrated in the accompanying drawings, in which—

Figure 1 is a top view showing the platform of a dummy-car with the improved track-clearer applied thereto. Fig. 2 is a bottom view of the same. Fig. 3 is a longitudinal sectional view of the improved track-clearer. Fig. 4 is a longitudinal sectional view of the grip mechanism, showing the position of the parts when the cable is dropped.

Similar letters of reference are used to designate like parts throughout the several views. A represents the platform or floor of a dummy-car. The forward end of this dummy is provided with a cow-catcher, fender, or pilot, B, consisting of a frame-work covered with a wire-netting and suitably attached to

the under side of the car-floor. Upon the lower edge of the pilot, and near each end thereof, are secured the boxes or bearings C, and through these bearings pass the rods D, provided upon their inner or rear ends with a spiral compression or retractive spring, E, while their outer or forward ends are connected by a metal rod or bar, F, of small diameter, and covered or incased by an india-rubber bar or rod, G, which extends the whole length of the rod F, between the two short spring-rods D D, as shown in Fig. 2. The rear ends of the rods D D are pivoted to the arms or rods H H, which constitute the forked end of the rod I, the rear end of which is pivoted to the lower arm of the bell-crank lever J, pivoted or supported by suitable bearings in a slot, K, made in the floor of the car. The upper arm of the bell-crank extends horizontally backward, and is connected by a short link, L, to the lever M, which is centrally pivoted to the forward end of the arc N of the grip-frame. The rear end of this said lever M is provided with a longitudinal slot, O, the object of which will be hereinafter more fully explained.

The grip mechanism consists of two gripping-jaws, P Q, operated by a lever, E, and pawl S engaging with a curved ratchet-bar, T, fully shown in Fig. 4. The arc N is provided with a longitudinal slot, U, (shown in Figs. 1 and 4,) and within the slot the curved or segmental ratchet-bar T moves forward and back, or up and down, being retained in position within the slot by means of the flat links V and W, the rear link, W, being pivoted within the slot, near or at the rear end thereof. The forward link, V, has a downwardly-projecting toe or tang, X, extending down past the pivotal point Y of the said link, and when in operation the tang engages with and enters the slot O in the lever M, as shown in Fig. 3.

The operation of the improved track-clearer will be as follows, to wit: When an obstruction is met with upon the track, the elastic rod G first receives the impact of the collision, which moves or forces the said rod backward toward the body of the pilot, and instantly operates through the medium of the connect-

ing spring rods and arms D, H, and I, and the bell-crank lever J, and depresses the slotted end of the lever-arm M, freeing the tang X from the slot O in the said lever-arm M, 5 and permitting the ratchet-bar T to rock or drop forward and downward from beneath the pawl S of the lever R, as clearly shown in detail in Fig. 4. This movement permits the lever R to tilt or drop forward by its own 10 gravity, and releases the pressure of the gripping-jaws upon the cable, allowing the upper jaw to rise sufficiently high to permit the cable to pass freely through the grip, or else drop out entirely, and the car, from being 15 freed from the pulling or drawing action of the cable, will be more readily brought to a standstill by the wheel-brakes, which should be applied simultaneously with the occurrence of the above-described operations. When the 20 obstruction has been removed from in front of the elastic bar G, the action of the retractive springs E will cause the elastic rod and the short rods D D to shoot forward to their original position, while the slotted end of the 25 lever M will be raised up, ready to engage with the tang X. The gripman may now place his hand under the ratchet-bar and raise it up to its normal position, when the moving of the link V upon its pivot will throw its lower end 30 or tang, X, down and into the slot O, ready for a repetition of the various actions described.

What I claim as the invention of HENRY M. TAAFFE, and desire to secure by Letters Patent

in the name of JANE MELEY, as administratrix of the estate of the late HENRY M. TAAFFE, 35 is—

1. A track-clearer having its pilot B provided with a forwardly-projecting transverse elastic or semi-elastic bar, G, strengthened by a central sustaining metal rod, F, held in position by spring-rod E E, and adapted to receive and transmit the impact of collision with an object upon the trackway to the grip mechanism.

2. A track-clearer having a transverse bar, 45 G, situated in advance of the pilot B, sustained by spring-rod D D, and connected by means of arms or rods H I, bell-crank lever J, link L, and lever M, with the grip mechanism, substantially as shown, for the purpose set forth and specified.

3. In a track-clearer, the cable-gripping device having a hinged ratchet-bar, T, moving within a slot, U, in the grip-arc N, and operated by a toe or tang, X, engaging with a slot in the lever M, connected by links, bell-crank, and rods, with a transverse bar, G, located in advance of the pilot B, substantially as shown and set forth, for the purpose specified.

JANE MELEY,
Administratrix of the estate of the late Henry M.
Taaffe.
